UNITED STATES PATENT OFFICE.

EDWARD H. ANGLE, OF PASADENA, CALIFORNIA.

TABLE.

1,359,479.

Specification of Letters Patent. Patented Nov. 23, 1920.

Application filed September 17, 1919. Serial No. 324,260.

To all whom it may concern:

Be it known that I, EDWARD H. ANGLE, a citizen of the United States, and a resident of Pasadena, in the county of Los Angeles, 5 State of California, have invented certain new and useful Improvements in Tables, of which the following is a specification, reference being had to the accompanying drawings.

10 My invention relates particularly to tables employed by dentists, surgeons or other such professional practitioners for carrying within easy reach the tools, implements, materials and devices as may be required while 15 operating, and is especially directed to tables adapted for the practice of orthodontia.

The principal object of my invention is to provide a table that may be moved lineally toward and away from the patient in 20 the chair, into the most convenient position for the needs of the operator.

Other object of my invention are to provide a table that may be moved with minimum effort, that will move smoothly to 25 avoid displacing implements or materials supported thereon, and that will maintain a definite relation to the chair irrespective of its distance therefrom.

My invention comprehends a table having 30 a portable base upon which it may be relatively reciprocated in parallel relation to the plane of said base.

The form of my invention as hereinafter described, comprises a table having an elongated top disposed transversely to the central longitudinal plane of an operating chair, and provided with spaced legs or standards having casters or rollers arranged to traverse suitably spaced tracks extending 40 parallel with said plane, on a portable base board plate. Said rollers and tracks coöperating to maintain a smooth and easy movement of said table toward and from said chair, in a lineal direction.

45 My invention also includes all of the various novel features of construction and arrangement as hereinafter more definitely specified.

In the accompanying drawings, Figure 1 50 is a perspective view of a table constructed in accordance with my invention; Fig. 2 is a transverse fragmentary sectional view of the base of said table, taken on the line 2—2 in Fig. 1, and conveniently showing a fragment 55 of the left hand leg; and Fig. 3 is a similar fragmentary sectional view of said

base, taken on the line 3—3 in Fig. 1, and conveniently showing a fragment of the right hand leg.

In said figures the table comprises the top 60 or tablet 1, legs 2 and 3 terminating in feet 4 and 5, and the base 6, which is preferably formed of a thin, flat panel of wood or slab or other suitable material.

The feet 4 and 5 are respectively provided with casters or rollers 7 and 8 mounted to rotate in suitable bearings 10 and 11, and to traverse tracks 12 and 13 which may preferably be formed of strap metal inlaid in said base 6, with their exposed surfaces 70 flush with the top surface of said base.

As shown in Figs. 1 and 2, the left-hand track 12 is provided with a small rib 15 extending longitudinally thereof, and arranged to engage in the grooves 16 in the 75 rollers 7, and coöperate therewith to guide the movement of the table in a lineal path, and to consequently cause the plain faced rollers 8 to traverse the plane surface of the right-hand track 13, as shown in Figs. 1 80 and 3.

The lineal movement of the table is arranged to be effected in parallel relation to the longitudinal plane of the operating chair, whose axis is indicated by the vertical dot and dash line 19 and whose circular base is indicated by the elliptical dot and dash line 20, the table base 6 being provided with the semi-circular indenture 22, for the convenient reception of said chair 90 base, thus affording a greater range of movement of the table toward the patient in the chair, and thereby permitting the operator to utilize the table as an arm-rest, which is to be desired in the delicate and 95 tedious operations incident to the practice of orthodontia.

It may be here noted that in the practice or orthodontia, it may be necessary to move the table toward and from the operating 100 chair many times during a single visit of a patient, and that in order that the table may be most convenient for the use of the operator, it must be capable of being moved forward and backward in a definite relation to the chair, in the easiest possible manner, so that the operator may instantly gain access to his instruments without unduly distracting his attention. Furthermore, the table must move smoothly so as 110 to avoid displacing the instruments or materials which may be supported thereon.

It will be obvious that by providing the left-hand track only with a guiding rib, the right-hand track may be flush with the surface of the table base, so as not to interfere 5 with the foot of the operator whose operating position is at the right of the chair.

I do not desire to limit my invention to the precise details of construction and arrangement as herein set forth, as it is obvious that various modifications may be 10 made therein without departing from the essential features of my invention as defined in the appended claims.

Having thus described my invention, I 15 claim:—

1. A table having a portable base, and provided with legs having rollers; the rollers of one leg being grooved, while the rollers of the other leg have plain cylindrical 20 surfaces; spaced tracks in the surface of

said base, one being flat upon which the plain surface rollers may roll, and the other having a longitudinally extended rib engaged in the groove of said grooved rollers.

2. A table having a base, and provided 25 with legs having rollers arranged to traverse the surface of said base in a lineal direction, said base having an indenture in one side thereof for the reception of the base of an operating chair with which said table 30 may coöperate, and tracks in said table base for said rollers, extended to embrace said chair base.

In witness whereof I have hereunto set my hand this 11th day of September, A. D. 35 1919.

EDWARD H. ANGLE.
